UNITED STATES PATENT OFFICE.

FRANK O. HARTMAN, OF MANSFIELD, OHIO

CIRCUIT-BREAKER.

No. 844,353.

Specification of Letters Patent.

Patented Feb. 19, 1907.

Application filed February 25, 1904. Serial No. 195,225.

To all whom it may concern:

Be it known that I, FRANK O. HARTMAN, a citizen of the United States of America, and a resident of Mansfield, in the county of Rich- 5 land and State of Ohio, have invented certain new and useful Improvements in Circuit- Breakers, of which the following is a specification.

My invention relates to improvements in circuit-breakers, and has particular reference to that class of circuit-breakers wherein is provided means for automatically opening or breaking an electric circuit upon the occurrence of a predetermined flow of current; and 15 my present invention is designed more particularly for the protection of high-potential circuits.

The objects of my improvement are, first, to provide a means for automatically opening or breaking an electric circuit upon the occurrence of an overload or a short circuit in combination with a means in the same device for opening the circuit by hand, thereby dispensing with the necessity for providing an 20 additional hand-switch in the circuit when it is desired to break the current manually; second, to prevent the resetting of the switch when an overload exists and to insure the automatic and instantaneous opening of the 25 switch when such conditions prevail irrespective of the fact that the operating-handle remains in the grasp of the operator; third, to provide a means for utilizing the current flowing from the high-potential circuit 30 to operate the tripping mechanism, as well as providing means for insulating the operating mechanism and frame therefrom.

A further object of my invention is to construct a circuit-breaker in such a manner as 35 to leave the movable laminated contacts and stationary terminals immersed in an insulating liquid whereby arcing is reduced to a minimum when the circuit is broken from any cause.

45 A special feature of my invention is in the means shown for operating and controlling the laminated bridging contacts and in bringing them in and out of engagement with the stationary terminals, the construction of my 50 device being such that the laminated bridging contacts reciprocate vertically and in direct alinement at all times with the stationary terminals.

An important feature of my invention is 55 the facility afforded in its construction for instantaneously breaking the circuit in case

of an overload or current on the circuit in excess of a predetermined amount when the operator is in the act of closing the circuit through the medium of the operating-handle 60 and clutch preparatory to locking the laminated bridging contacts in closed position.

I attain these and other objects by the mechanism illustrated in the accompanying drawings, in which— 65

Figure 1 is a view in perspective looking from the rear showing the circuit-breaker in open position, one of the casings being removed. Fig. 2 is a similar view taken from the front, showing the circuit-breaker in 70 closed position. Fig. 3 is a view in vertical cross-section showing the locking mechanism and trip. Fig. 4 is a detail view, partly in section, of the locking mechanism and clutch; and Fig. 5 is a view in vertical cross- 75 section taken on a line at right angles to Fig. 3, showing the laminated contacts, the trip, and locking mechanism.

In constructing my device I provide a suitably-supported bracket 1, from which projects a table 2 at an angle therefrom, the table being provided on two opposite sides with a series of apertures 2^a 2^a, according to the number of contacts or terminals employed, the apertures being countersunk, as at 3^a, 80 and adapted to receive tubular bushings 2^b 2^b, of some suitable insulating material, the bushings each provided with a circular groove 3^b, designed to receive a leaden ring 3, the size of which ring is such that a portion 85 thereof rests in the countersunk recess 3^a, surrounding the aperture 2^a. A locking annulus 4 snugly fits around each bushing, the annuli each provided with a groove 5, formed 90 therein to engage the exposed portions of the rings 3 3. Each annulus is fastened to the table by suitable means, as the screws 6, whereby to firmly engage the rings 3 3 and retain the bushings 2^b rigidly in position. 95

Depending from the table are a plurality 100 of rectangular casings 63 63, corresponding with the number of movable contacts employed, the casings preferably extending transversely across the table and consisting of a metallic box lined with a suitable non- 105 conducting material, as shown at 64. Ribs 65 are removably secured to the table, the upper edges of the casings being secured to the ribs in any convenient manner.

The bushings are of such length as to project some distance above and below the surfaces of the table 2, the bushings depending 110

into the casings, each casing adapted to inclose two bushings, one on each side of the table. The casings are each filled with oil to minimize the danger of arcing when the contacts are broken, the lining 64 preventing the communication of a current from the contacts to the casing 63.

The hollow insulating bushings 2^b project into the oil or other fluid in the casings and are provided at their lower ends with cushioning-sleeves 66 66, of wood or other non-conducting material. Passing through each bushing and its attached sleeve is a stationary contact member 7, the upper portion of which is threaded to receive a nut 8, seated in a recess 60, formed in the upper end of the bushing, the nut being cushioned by means of a packing 67 and operating to sustain the contact member relative to the bushing. The threaded ends of the contact members project some distance above the bushings for a purpose hereinafter set forth, and their lower ends terminate in enlarged feet 68, lying adjacent the sleeves 66, which feet are engaged by the movable contact members, as presently to be described. The feet are each provided with an extension 69, removably secured thereto in any convenient manner, as shown, these blocks 69, being the last points engaged by the movable contacts when the circuit is being broken and being removable, so that in case they become burned by arcing new blocks can be easily and quickly substituted therefor at a minimum cost; thus avoiding the necessity of substituting an entire new stationary terminal. The blocks are preferably formed of brass.

Each case 63 contains a pair of stationary terminals spaced apart from each other. Inserted in the table 2 at a point preferably midway between the stationary terminals is an apertured bearing-block 30, of wood, which is removably secured to the table in any suitable manner. A rod 29, of wood or other non-conducting material, passes through the aperture in the block, the block being of some depth to afford a bearing for the rod and prevent lateral play thereof, the rod being provided with a shoe 31 at its lower end, having a corrugated socket 33, in which the rod is received, a pin 32 passing through both rod and socket to secure the shoe to the rod. The lower face of the shoe is oppositely-inclined, as shown, and is provided with a holder 35, laminated bridging contacts 34 34 being received between the holder and shoe and the whole being removably secured by fastening means 36 to the shoe. The ends of the laminated sheets 34 34 engage the feet 68 of the stationary terminals in the usual manner, one of the exterior sheets being elongated and provided with a removable contact-block 70 for engagement with the block 69 to reduce the

point of engagement between the stationary and movable contact members, whereby the liability of arcing when the circuit is broken is reduced to a minimum.

The rod 29 is adapted to reciprocate through the bearing-block 30, the rod being of sufficient length so that the movable bridge-contact at its lower end is always submerged in the liquid in the casing.

A cross-head 27 extends transversely of 75 and above the table 2, the cross-head having threaded apertures 71, in which the upper ends of the rods 29 29 are received and secured. This cross-head is also provided with hollow bosses 28, the upper ends of 80 which removably receive adjustable caps 72, to which are secured the springs 73, the opposite ends of the springs being secured to the nuts 74, removably secured to the table 2, the hollow bosses forming casings in which 85 the springs are received when the circuit is broken and the bridge-contacts lie in their lowermost positions, as shown in the dotted lines 37 37 in Figs. 3 and 5. The cross-head is furthermore provided with lugs 38 38, in 90 which is journaled a pin 39.

Suitably journaled in the bearing 61 of the bracket 1 of the frame is the rod 42, it being prevented from endwise movement by the removable screw 75. The inner end of the rod 95 has secured thereto the crank-disk 44, a stud 45 passing through the rod and crank-disk to prevent the rotation of the disk relative to the rod. A link 46 is pivotally secured at one end to the disk 44 and eccentrically 100 thereof by means of a stud 47, the opposite end of the link being pivotally secured to a shackle 48, to which shackle is pivotally secured a lever 50, one end of the lever being journaled upon a stud 51, located in a slot 62 105 in the bracket 1, and its opposite bifurcated end embraces the shank 41 of a hook 40, the shank being pivotally secured intermediate its ends to the bifurcated end by means of a stud 53. A leaf-spring 56 is secured to the 110 hook at one end, the opposite end of the spring engaging the lever 50, whereby to prevent the movement of the hooked end of the shank toward the lever from a position at substantially right angles thereto. The upper projecting end of the shank has secured thereto an upturned arm 54, lying above the lever 50, to which lever is secured a leaf-spring 55, the free end of which engages the 115 arm to normally retain the shank in a vertical position and cause the hook 40 to engage the roller 39, as will be hereinafter set forth. It will also be observed that the crank-disk, link, and shackle constitute a toggle connection between the rod 42 and the lever 50. 120 The outer end of the rod has rigidly secured thereto a clutch-collar 57, having the projection 57^a, and a corresponding clutch member 58 is loosely journaled on the shaft, the latter member provided with a projection 58^a, 125

adapted to engage the projection 57^a, whereby to rotate the shaft and through the medium of the crank-disk, link, and shackle to draw the lever 50 and the hook 40 down, so 5 that the hook will engage the roller or pin 39 upon the completion of a semirotation of the rod 42, the reverse rotation of the rod then operating to raise the bridge-contacts into engagement with the stationary terminals 10 and close the circuit. The clutch member 58 is provided with a suitable handle 59, whereby to rotate the rod, and a stop 76 is located on the table, the stop adapted to be engaged by the crank 44, whereby to prevent a complete rotation of the rod 42. When the toggle is extended, the bridge-contacts are brought into engagement with and held against the stationary terminals, the springs 73 73 being placed under tension by being 15 expanded. When it is desired to manually break the circuit, the arm 54 may be depressed by hand, thereby swinging the hook 40 outward and releasing the cross-head, which at once descends, owing to the tension 20 of the springs 73 73, and by reason of its weight or the shaft 42 may be rotated, which will pull down the lever 50, thus lowering the hook 41 and permitting the springs 73 73 to force the cross-head and the bridge-contacts 25 away from the stationary terminals. The hook 40 is inclined, as shown, whereby to slide over the pin 39, the spring 56 always preventing the hook from riding in front of the pin and the spring 55 causing the hook to catch under the pin. 30

A supporting-bar 9 is received upon the projecting end of one of each pair of stationary terminals, a jam-nut 10 being placed above the bar on the terminal 7 to retain the 35 bar in place. The bars 9 9 project parallel with and laterally of the table and are adapted to support the solenoid-coils 11, each of which coils has a centrally-disposed longitudinally-extending tube 12 received therein 40 and extending below and above the coil, the tube being open at its upper end and lined with a suitable fiber 77 part way of its length. In the lower portion of the tube is secured a second tube 78, threaded at its lower end for 45 the reception of a nut 79, having a threaded aperture extending therethrough, wherein is received the adjusting-screw 17, upon the upper end of which rests a core 16, movable within the tube and adjustable therein by 50 means of the screw 17. The lower ends of the coils are seated in the bar 9, their upper ends being received in a plate 14, which latter is provided with a binding-post 80 at its outer end, the plate being suitably secured 55 by means of a bolt 81, extending between the supporting-bar 9 and the plate 14, the bolt being insulated from each by means of the thimbles 82 and being inclosed within the hollow standard 13, which latter is formed of 60 some suitable non-conducting material.

The upper end of the tube 12 projects through the plate 14 and is provided with an apertured cap 15, in which is loosely received the double-headed releasing-pin 18.

A standard 24, projecting from the bracket 1, supports the horizontally-extending rod 26, which supports a hanger 25, and journaled in the hanger and in the standard is a shaft 23, the shaft adapted to have the sleeves 83 adjustably secured thereto, the collars each 75 provided with a socket 21, in which is received and secured one end of an inclined rod 20 of suitable insulating material, the opposite or free ends of the rod carrying the frustoconically-shaped collars 19, adjustably secured thereon. The collars rest on the upper ends of the releasing-pins 18 and are conical in order that a good full contact may be made with the pins in view of the inclined positions of the rods 20. Secured upon the 80 shaft 23 is a trip 22, projecting in a direction opposite to that taken by the rods 20, the trip extending over and in close proximity to the arm 54 when the latter is in its normally raised position, as when the bridging contacts are being held in engagement with the 85 stationary terminals.

The current enters through the plate 14, whence it passes through the solenoid to the supporting conducting-bar 9, thence to the 90 stationary terminal 7, with which conductor 9 is connected, thence across the laminated bridge-contact to the opposite stationary terminal, from whence it is taken by means of the insulated wire 84, removably secured to 95 the projecting threaded end of the stationary terminal by means of the coupling 85.

When several bridge-contacts are used, as in practice, I provide a shield 86 of any suitable non-conducting material or fiber, which 100 is secured to one edge of the table and extends therealong to protect the depending portions of the solenoid-tubes 12 and prevent contact therewith, since the depending portions are "live," and to separate them from 105 the frame of the apparatus. Furthermore, I provide a casing 87, formed of laminated sheets of insulating material, in which case 110 are mounted the solenoids, and between each two of solenoid-coils is located an insulating- 115 plate 89 to separate the coils.

The bracket 1 is provided with a plurality of apertures 88 to admit of the attachment 120 of the circuit-breaker to the switchboard. (Not shown.)

From the foregoing it will be observed that the handle is turned in one direction—say toward the right—to lower the lever 50 and cause the hook 40 of the catch 41 to engage the pin 39 on the cross-head, the handle and 125 the rod then being rotated in the opposite direction to raise the cross-head and laminated bridge-contacts, since a further movement of the crank 44 toward the right is prevented by the stop 76; but by reason of 130

the fact that there is but one tooth 57^a and 58^a on each of the clutch members the handle will loosely rotate on rod 42 until its tooth once more engages the tooth on the 5 fast member of the clutch, whereupon a half-rotation to the left will straighten the toggle, thereby raising the lever 50 and the cross-head until the laminated contacts are pressed tightly against the stationary terminals and the springs 73 extended. As heretofore set forth, the circuit can be manually broken by reversing the rotary movement of the handle, which will of course depress the lever. In the event of an overload 15 on the circuit, however, when the laminated contacts are in their raised position the increased current entering the solenoid attracts the loose core 16 in the usual manner and causes it to impinge smartly against the 20 lower head of the releasing-pin 18, which in turn imparts an oscillatory movement to the shaft 23 through the medium of the rod 20, thereby causing the trip-arm 22 to engage and depress the arm 54 and rock the catch 25 41 on its pivot 53 and against the tension of spring 55, whereby to release the pin 39 and permit the instant breaking of the circuit. In this connection it will be noted that the arm 54 and the catch 41 constitute, in effect, a bell-crank. The stop 76 is so located 30 that the toggle-joint formed by the link 46, shackle 48, and disk 44 passes slightly beyond its dead-center when in extended position, the disk resting against the stop, which thus operates to prevent any slight jar or 35 other inadvertent movement from opening the circuit by breaking the toggle, since as soon as the toggle is broken the tension of 40 springs 73, as well as the weight of the bridging-contact members, will force the latter away from the stationary terminals. The springs insure a quick break upon the occurrence of an overload and counteract any 45 tendency of the movable contacts to stick or "freeze," and the tension of the laminated sheets assists this movement. In the event that the operator endeavors to close the circuit during the continuance of an overload the following operation will take place: The 50 lever 50 being in its upright position, the operating-rod 42 is rotated toward the right to lower the lever and its catch 41, so that the hook 40, carried thereby, may engage the cross-head. The rod is then rotated in 55 the opposite direction until the laminated bridge member is brought into contact with the stationary terminals, whereupon the circuit is completed and the electroresponsive mechanism energized to cause the partial rotation of the shaft 23 and its trip 22, the latter being brought down upon the arm 54 of the catch to cause its release from its cross-head and permit the latter to descend to 60 break the circuit while the handle 59 remains in the grasp of the operator. Thus it

will be seen that it is impossible to close or complete the circuit during the continuance of an overload.

As will be observed, the drawings disclose a mechanism known as a "three-pole" circuit-breaker; but it is plain that it can be constructed in single, two-pole, or four-pole combination or more by using a lesser or greater number of units. It is further obvious that many changes might be made in the form and arrangement of the several parts described without departing from the spirit and scope of my invention, and hence I do not wish to limit myself to the exact construction herein set forth; but,

Having fully described my invention, what I claim as new, and desire to secure by Letters Patent, is—

1. The combination with a circuit-breaker, a plurality of stationary terminals, a movable bridge-contact adapted to engage the terminals and a supporting means secured to the bridge, a rod and lever, a toggle connecting the rod and lever, and a catch on one end of the lever for holding the bridge in contact with the terminals.

2. The combination with a circuit-breaker, a plurality of stationary terminals, a movable bridge-contact adapted to engage the terminals and a supporting means secured to the bridge, a rod and lever, a toggle connecting the rod and lever, a catch on one end of the lever for holding the bridge in contact with the terminals and means on the rod for operating the catch.

3. A circuit-breaker comprising a plurality of stationary terminals, a bridge-contact for engaging and connecting the terminals, a supporting member to which the bridge-contact is secured, a manually-operable rotatable rod independent of and removed from the bridge-contact-supporting member, a suitably-supported lever, a toggle connecting the rod and lever and a catch on the lever for releasably engaging the supporting member.

4. A circuit-breaker comprising a plurality of stationary terminals, a bridge-contact for connecting the terminals, a supporting member to which the bridge-contact is secured, a rotatable manually-operable shaft, a suitably-supported lever located apart from the supporting member, a toggle connecting the shaft and lever, a stop for limiting the movement of the shaft in one direction and a catch adapted to releasably engage the contact-supporting member.

5. A circuit-breaker comprising stationary terminals, a bridge-contact connecting the terminals, a supporting member to which the bridge-contact is secured, a rotary manually-operable shaft, a crank secured thereto, a link loosely secured to the crank, a shackle loosely secured to the link, a pivotally-supported lever releasably connected to the contact-supporting member to which the shackle

- is also loosely secured, and a catch carried by the lever and releasably engaging the contact-supporting member.
6. The combination of a plurality of electric switches, each switch consisting of separated terminals, and a bridging member for engaging said terminals, a horizontally-journalized rotatable operating-arm, a lever, a toggle connecting the arm and lever, means on the lever for engaging the bridge, bringing it in contact with the terminals, and means for releasing said bridge automatically upon the occurrence of an overload, and preventing the closing of said bridge while the overload continues.
7. A circuit-breaker comprising stationary terminals, a bridge-contact connecting the terminals, a supporting member to which the contact is secured, a suitably-pivoted lever located apart from and independent of the supporting member, means for oscillating the lever comprising a means for locking the lever in one position, a catch pivotally secured to the lever and adapted to releasably engage the supporting member to temporarily connect the lever and supporting member, an arm carried by the catch and electroresponsive means for causing the release of the catch from the supporting member.
8. A circuit-breaker comprising stationary terminals, a bridge-contact removably engaging the terminals, a supporting member to which the bridge-contact is secured, a rotary rod, a pivotally-supported lever, means connecting the rod and lever, a catch releasably engaging the supporting member, a handle loosely mounted on the rod and co-operating clutch members carried by the handle and rod respectively.
9. In a circuit-breaker, the combination with a stationary terminal, of a supporting-bar, mounted upon and in electrical connection with the terminal, a connecting-plate, and an electroresponsive means connected between and electrically connecting the connecting-plate and supporting-bar.
10. In a circuit-breaker, the combination with a stationary terminal, of a supporting-bar mounted upon and in electrical connection with the terminal, a connecting-plate, an electroresponsive device located between and electrically connecting the connecting-plate and the supporting-bar, and an insulated brace extending between and mechanically connecting the connecting-plate and supporting-bar.
11. In a circuit-breaker, the combination with a stationary terminal, of a supporting-bar secured thereto and projecting laterally therefrom, a connecting-plate, an electroresponsive device secured between the bar and plate, insulating-sleeves passing through the bar and plate and a brace received within the sleeves and connecting the bar and plate.
12. In a circuit-breaker, the combination with a stationary terminal, of a supporting-bar secured to the terminal, a connecting-plate, a solenoid-coil located between the connecting-plate and supporting-bar, a fiber-lined tube in and forming a part of the solenoid, the tube depending some distance beneath the solenoid-coil, a core adjustably located within the tube, a suitably-supported rotary shaft, a rod carried by and projecting from the shaft, an arm also carried by the shaft, the rod extending to a point adjacent the solenoid, a pin engaged by the core for actuating the rod, a movable bridge-piece, means for raising and retaining the bridge-piece in contact with the stationary terminal and an arm on the last-named means, the last-named arm adapted to be engaged by the arm on the shaft for releasing the engagement of said means and the movable bridge-piece.
13. In a circuit-breaker, the combination with stationary electrodes, a bridge-contact for connecting the electrodes and means for bringing the contact into engagement with the electrodes, of a connecting-bar secured to one of the electrodes, a solenoid carried by the connecting-bar and in circuit therewith and with the main-line circuit, a suitably-supported rotary shaft, a rod adjustably mounted on the shaft and extending to a point adjacent the solenoid whereby it is actuated, a member also carried by the shaft adapted to impinge against the contact-actuating means for releasing the contact from the means.
14. In a circuit-breaker, the combination with a frame, of stationary terminals, a bridge-contact adapted to connect the terminals and means releasably connected with and independent of the bridge-contact member for bringing it into engagement with the terminals, a solenoid connected with one of the terminals, insulating means located between the solenoid and the circuit-breaker frame, a suitably-supported stationary bar, a hanger carried by the bar, a rotatable shaft mounted in the hanger, a rod adjustably secured to the shaft, electrically-operated means for actuating the shaft, and an arm actuated by the shaft for impinging the contact-actuating means and causing the release of the bridge-contact therefrom.
15. The combination in a multipolar circuit-breaker, with a single table, of a plurality of independent casings, stationary terminals supported by the table, their lower ends received in the casings, a bridge-contact in each of the casings for connecting the terminals, a series of solenoids connected with certain of the stationary terminals, means for connecting each of the solenoids to a circuit, insulating-plates located between each two adjacent solenoids, a casing in which the solenoids are mounted, releasable manually-operated means for bringing the contacts into engagement with the stationary terminals.

and means actuated by the cores of the solenoids for releasing the bridge-contact from its manually-actuated engaging means.

16. In a circuit-breaker, the combination with a plurality of stationary terminals, of a movable bridge-contact for connecting the terminals, a lever, means carried by the lever for releasably engaging the movable contact, manually-operated means connected with the lever and actuating the latter to cause the engagement and disengagement of the lever and the movable contact, a solenoid in electrical circuit with one of the stationary terminals, a rocking member, means carried by the rocking member and actuated by the solenoid for rocking the member and a separate means carried by the rocking member and adapted to impinge the releasable engaging means to cause the automatic release of the movable contact.

17. In a circuit-breaker, the combination with a stationary terminal, of a supporting-bar secured thereto and projecting laterally therefrom, a connecting-plate, an electro-responsive device secured between the bar and plate, insulating-sleeves passing through the bar and plate and a brace received within the sleeves and connecting the bar and plate.

18. The combination of a plurality of electric switches, each consisting of separated terminals and a bridging member for engaging said terminals, a horizontally-positioned rotatable operating-arm journaled in the frame of the circuit-breaker for bringing said bridging members into engagement with the terminals, a toggle for locking said bridging members in such position, and means for effecting the automatic and simultaneous release of said movable contacts and positively 40 and actually disconnecting the same from the operating-arm upon the occurrence of an overload.

19. An electric switch consisting of movable and stationary contacts, a horizontally-positioned rotatable operating-arm journaled in the frame of the circuit-breaker for bringing said movable contacts into engagement with said stationary contacts, a pivotally-supported lever located apart from the operating-arm, a toggle connecting the arm and lever and locking said switches in normal position, and one or more solenoids operating to release and absolutely disconnect said movable contacts from said operating-arm upon the occurrence of an overload on the line, and preventing the closing of said switches, while such overload exists.

20. The combination of a plurality of electric switches, each switch consisting of separated terminals, and a bridging member for engaging said terminals, a horizontally-positioned rotatable operating-arm journaled in the carrying-frame of the circuit-breaker, a single means connected with the operating-arm and temporarily engaging the bridging

member for bringing said bridging member into engagement with the terminals, a toggle constituting a portion of the connecting means for locking said bridging members in such position, and one or more solenoids 70 mounted on the carrying-frame of the circuit-breakers, energized by current from the high-potential circuit and operating to absolutely release the engagement of the bridging members with the connecting means upon the 75 occurrence of an overload.

21. The combination of a plurality of electric switches, each switch consisting of separated terminals and a movable member for engaging said terminals, a rotatable operating-arm journaled horizontally in the carrying-frame of the circuit-breaker for bringing said movable members into engagement with the terminals, a pivotally-supported lever located apart from the operating-arm, a toggle permanently connecting the operating-arm and lever for locking said movable members in closed position, means releasably connecting the lever and movable members, means for absolutely disconnecting said 90 movable members automatically from the lever upon the occurrence of a predetermined overload, and means for manually releasing said movable contacts and permitting the unrestricted movement of said movable members by turning said operating-arm in the direction opposite to that taken in closing the switch.

22. The combination of a plurality of electric switches, each switch consisting of separated terminals, and a bridging member for engaging such terminals, a horizontally-journaled rotatable operating-arm, a lever located apart from the operating-arm, a toggle permanently connecting the lever and 105 arm, said arm operated for bringing the bridging member into engagement with the terminals and locking them in such position, means carried by the lever for releasably connecting the lever with the bridging member, and one or more solenoids mounted on insulators in electrical contact with one of the terminals of each switch, said solenoids operating collectively or separately for releasing the bridging contacts upon the occurrence of an overload.

23. An electric switch consisting of separable contacts to open and close the circuit, a toggle for locking the movable member of such switch in normal position, means for absolutely disconnecting said movable member automatically from its operating means upon the occurrence of a predetermined overload, and means for absolutely disconnecting said movable member manually from its 120 operating means.

24. In a circuit-breaker, the combination with a plurality of stationary terminals and a bridging contact movable toward and from the terminals, of a rotatable manually-oper- 130

ated shaft, a lever pivoted at a point distant from the shaft, a link connecting the lever, and shaft, means pivotally secured to the lever, the means adapted to engage the bridging contact to raise and hold the same against the terminals, and electroresponsive means adapted to impinge against the catch to cause a total disconnection of the catch and its connected parts and the bridging contact to release the latter.

25. In a circuit-breaker, the combination with stationary terminals, and a bridging contact movable toward and from the terminals, of a catch for releasably engaging the bridge-contact, manually-operating mechanism to which the catch is pivotally secured

for moving the catch into engagement with the bridging contact when the latter is in its position removed from the terminals, to move the bridge into engagement with the terminals, and electroresponsive means, a rod, a shaft, said rod connected to the shaft, and a trip mounted on the shaft adapted to engage the catch to cause it to release the bridging contact irrespective of the operating means. ²⁵

Signed at Mansfield, Ohio, this 15th day of January, 1904.
